Primary Examiner — Jeffrey D Asch*(74) Attorney, Agent, or Firm* — Banner & Witcoff, Ltd.**(57) CLAIM**

The ornamental design for a handset, as shown and described.

DESCRIPTION

FIG. 1 is a perspective front view of a handset showing my new design;

FIG. 2 is a front plan view thereof;

FIG. 3 is a rear plan view thereof;

FIG. 4 is a right side view thereof;

FIG. 5 is a left side view thereof;

FIG. 6 is a top plan view thereof; and,

FIG. 7 is a bottom plan view thereof.

The broken lines and the unshaded regions within the broken lines show portions of the handset and form no part of the claimed design.

1 Claim, 5 Drawing Sheets(56)
